UNITED STATES PATENT OFFICE

129,263

DESIGN FOR A RIGID AWNING

James J. Morrison, Saratoga Springs, N. Y.

Application May 8, 1940, Serial No. 92,216

Term of patent 14 years

To all whom it may concern:

Be it known that I, James J. Morrison, a citizen of the United States, residing at Saratoga Springs, county of Saratoga, and State of New York, have invented a new, original, and ornamental Design for a Rigid Awning, of which the following is a specification, reference being had to the accompanying drawing, forming a part thereof, in which the single figure in the drawing is a perspective view of a rigid awning showing my new design, both sides thereof being the same.

The characteristic feature of my design resides in the combination on a rigid awning of the configuration disclosed of the lower side and front edges formed by alternate straight and arcuate portions, the lower ends of the dark and light stripes terminating in the said straight and arcuate portions, respectively, all as shown.

I claim:

The ornamental design for a rigid awning, as shown and described.

JAMES J. MORRISON.
